UNITED STATES PATENT OFFICE.

WALTER E. PARR, OF SPARTA, MISSOURI.

LUBRICATOR.

No. 913,553.

Specification of Letters Patent.

Patented Feb. 23, 1909.

Application filed June 5, 1907. Serial No. 377,369.

To all whom it may concern:

Be it known that I, WALTER E. PARR, a citizen of the United States, residing at Sparta, in the county of Christian, State of Missouri, have invented certain new and useful Improvements in Lubricators; and I do hereby declare the following to be a full, clear, and exact description of the invention, such as will enable others skilled in the art to 10 which it appertains to make and use the same.

This invention relates to oil cups and more particularly to that class which are automatically operated.

15 The object of the invention is to provide an oil cup including a thermostatic device which will be expanded by the heat generated from the bearing in connection with which the cup is used, to open the valve of the cup 20 and permit flow of lubricant to the bearing, and the invention not only resides in the provision of such a thermostatic device but also in the provision of a novel form of valve which may be adjusted so as to be opened to 25 a greater or less degree when operated by the thermostatic device, depending upon the nature of the bearing and other conditions which might prevail.

In the accompanying drawings, Figure 1 is 30 a view in elevation of an oil cup embodied in my invention, Fig. 2 is a detail vertical sectional view taken centrally therethrough, Fig. 3 is a similar view but considerably enlarged and taken through the valve and the 35 thermostatic device, Fig. 4 is a detail perspective view of the thermostatic device removed from the cup, and, Fig. 5 is a similar view of the valve and its stem removed from the cup.

40 As shown in the drawings the device comprises a reservoir constructed of the usual cylindrical glass case 7 and the upper and lower heads 8 and 9 respectively which are flanged and between which the cylindrical glass case 7 is clamped. Formed integral 45 with the heads 8 and 9 are tubular sections 10 and 11 respectively which have a threaded connection with each other as at 12 whereby the heads may be brought together to clamp 50 the cylindrical glass case as above stated. The tubular section 11 is provided adjacent its point of connection with the head 9 with an opening 12' for the passage of oil from the cup formed by the heads and the cylindrical glass case, into the feed nozzle 13 for the cup, 55 which nozzle terminates in the usual thread-

ed nipple 14 whereby the cup may be connected with the bearing which it is to lubricate. Swiveled upon the top of the head 8 is the usual closure plate 15 for the filling 60 opening 16 in the said head.

Formed within the tubular section 11 at the point of junction of the same with the lower head 9 is a valve seat 17 upon which a valve 18 normally rests, the said valve being provided with a stem 19 which projects into the tubular section 10 and is provided with a squared portion at its upper end, the said portion being indicated by the numeral 20. This squared portion extends into a squared 70 socket 21 formed in the stem 22 of a turn button 23, it being understood of course that the button may be turned to rotate the said valve stem and the purpose of this rotation will be presently described. The stem of the 75 turn button is loosely received in a bore formed in a threaded sleeve nut 24 which sleeve nut is removably threaded into the upper end of the tubular section 10. A spring 25 is engaged upon the valve stem 80 above mentioned and bears at its lower end against a collar 26 formed integral with the said valve stem adjacent the lower end thereof and at its upper end against the lower end of the stem of the turn button and this 85 spring serves to normally hold the valve to its seat as heretofore stated.

In the lower end of the valve stem there is formed a threaded bore 27 in which is engaged the threaded upper end portion of a 90 stem 28, the lower end of the stem being extended into an inverted hollow conical drip member 29 which is secured concentrically to the stem by means of connecting portions 30. Formed integral with the drip member is an 95 arm 31 which is offset at its lower end as at 32 and squared as at 33 for reception in a squared socket 34 formed in the thermostatic member of the valve. This member is cylindrical in form and comprises a pair of sections 100 which have hinged connection with each other and which are hollow so that when the members are connected they form a cup in which is contained volatile fluid and the thermostatic member when so filled with fluid is 105 placed within the feed nozzle 13 for the valve and rests upon the shoulder 34 formed by a reduction 35 in the bore of the nozzle, there being an annular series of lugs 36 formed integral with the shoulder to support the thermostatic member in slightly raised position 110 with respect thereto so as to permit of passage

of the lubricant around the member and beneath the same and through the threaded nipple 14.

From the foregoing description of my invention it will be observed that should the bearing have heat to any appreciable degree, the fluid within the thermostatic member will be volatilized thus causing the member to expand and lift the valve from its seat through the instrumentality of the arm 31 and the drip member 29, it being understood that the oil will flow along the stem 28 and into and through the said member 29 and will drip therefrom to the bearing.

It will be understood from the foregoing that by reason of the fact that the arm 31 is squared at its lower end and seated in a squared socket, it will be held stationary when the turn button before mentioned is turned and that consequently the turning of this button will result in a vertical adjustment of the arm and that such vertical ad-

justment will result in an adjustment of the valve so that it will be open at a certain predetermined degree of heat.

25

What is claimed is—

A lubricator comprising a container, a nozzle leading from the container, a valve normally closing communication between the container and the nozzle, a hollow expansible container located within the discharge nozzle, an arm having an integral stem which has threaded adjustable connection with the valve, the arm having positive connection with the said hollow expansible container, a stem for the valve, and means whereby the stem may be turned to adjust the arm with respect thereto.

In testimony whereof, I affix my signature, in presence of two witnesses.

WALTER E. PARR.
